UNITED STATES PATENT OFFICE.

ABRAM E. SMITH, OF NEW YORK, N. Y.

TANK CAR.

Application filed February 23, 1921. Serial No. 447,178.

To all whom it may concern:

Be it known that I, ABRAM E. SMITH, a citizen of the United States, residing at New York city, borough of Manhattan, in the county of New York and State of New York, have invented certain new and useful Improvements in Tank Cars, of which the following is a specification.

My invention relates to tank cars of that character or type adapted to transport material in bulk, and particularly contemplates a tank body adapted to contain those materials, such, for example, as high-viscosity hydrocarbons, which are flowed in liquid form into the tank but which may become congealed or increased in viscosity, due to temperature conditions, to such an extent as to prevent ready flow thereof from the tank when it is desired to withdraw same therefrom. Tank cars for the purpose stated have hitherto been provided with heating means whereby the congealed or solidified contents may be reduced in viscosity or increased in fluidity so as to permit such contents to flow readily from the tank. Such means have usually consisted of closed heating coils or members arranged within the body of the tank and adapted to receive a supply or current of steam whereby the contents of the tank may be heated. The known constructions just described have, to some extent, been unsatisfactory or undesirable, in that the heating coils or members when located within the tank body occupy considerable space therein, thereby reducing the carrying capacity of the tank, and, further, because the point at which the car is located or discharged is often inconveniently situated as regards a supply of steam or other heating fluid as the heating medium. My present invention contemplates the provision of heating means which will not be dependent upon a supply of steam or other heating fluid from an extraneous source, but which will be co-constructed that the heating agent may be, if desired, carried by the car itself, and, more specifically, in providing heating means which will be located external to the car body and, therefore, not reduce the carrying capacity of the car to an objectionable extent.

The invention consists in the improvements to be more fully described herein-

after, and the novelty of which will be particularly pointed out and distinctly claimed. 55

I have fully and clearly illustrated a preferred embodiment of my invention in the accompanying drawings, to be taken as a part of this specification, and wherein—

Figure 1 is a view in side elevation, partly 60 in section, and with parts broken away, of one embodiment of my invention;

Figure 2 is a top plan view, partly in section, of the structure shown in Fig. 1, and

Figure 3 is a transverse section on the line 65 3—3 of Fig. 1.

Referring to the drawings by characters of reference, 1 designates generally the understructure of a car, the same being shown for the purposes of illustration of this invention as being of a well known commercial type. The understructure may include a center sill made up of longitudinally extending flanged girders arranged with their intermediate webs 2 in parallel vertical 70 planes, respectively, on opposite sides of the longitudinal center of the car, the upper and lower flanges 3, 4 of said girders being directed outwardly, as clearly shown in Fig. 3 of the drawings. The girders 2 are connected rigidly by upper and lower horizontal plates 5, 6 secured to the flanges 3, 4, respectively, in any suitable manner, as by rivets 7 passing through the side edge portions of said plates and through said flanges 3, 4. 85

At the end portions of the center sills are suitably supported bolsters 8, of any suitable commercial construction, adapted to rest on trucks (not shown) carrying running wheels 9 adapted to travel on the usual rails 9^a of a railway track, and at intermediate portions of the underframe are outwardly extending transverse members 10, also secured at their inner ends by suitable rivets 10^a to the center sill. The bolsters 8 and members 95 10 support flanged side sills 11 of the understructure, said side sills being secured at their lower flanges 11^a by rivets 12 to the outer end portions of said members 8 and 10. The members 11, at their ends, are riveted to the end sills 13 of the understructure, whereby the understructure includes a rectangular frame. Supported on the rectangular frame is a tank body, shown generally at 14, and including a bottom plate 105 15 lying in substantially a horizontal plane,

but preferably dished or depressed at its central longitudinal portion, and having its longitudinal side edges resting on the upper flanges 11^b of the side sills 11, said bottom 5 plate resting at its central portion on the center sill and being secured to the flanges 3 of the latter by the rivets 7, heretofore described.

Supported by the side sills 11 are the vertical side walls 16 of the tank body, the lower edges of which are secured to said side sills by angle-irons 17 inside of the tank body, the vertical members of which are riveted to the side walls, as at 18, and the 15 horizontal members of which, respectively, rest upon the outer edges of the plate bottom 15, said members and plate being secured to the upper flanges 11^b of the side sills by rivets 19. The upper portion of the 20 tank body is closed by a top wall 20, the outer side edges of which are secured to the upper edges of the side walls 16 by means of angle-irons 21, the flanges of which are riveted, respectively, to the wall 20 and the 25 side walls by rivets 22, 23. The ends of the tank are closed by end walls 25, riveted to the top, bottom and side walls, as at 25^a, in the same manner as heretofore described for connecting said top and side walls, and side 30 and bottom walls. The tank is provided with a suitable dome 26, through which the tank is filled with the material to be transported, and the tank is also provided with suitable draw-off duct or ducts (not shown) 35 by means of which the contents are withdrawn from the tank. It will be seen that by the construction just described, a tank body is provided which is substantially rectangular both transversely and longitudinally.

I will now describe improved means for heating the body of the tank in order to melt or render fluid any contents which may be congealed or so viscous as not to flow readily when it is desired to withdraw the same from the tank. This means, in its preferred embodiment, consists of a plurality of heating chambers or furnace chambers arranged beneath the tank body, and 45 having means for heating the same so as to transmit the heat to the bottom wall of the tank and thereby melt the material carried by the latter. These furnace chambers are shown generally at 27, each of the same being 50 preferably rectangular in form, a plurality of such chambers being provided, arranged side by side, lengthwise of the car, and on opposite sides of the center sill. Each of the heating chambers comprises a 55 bottom wall 28, vertical side walls 29, a rear wall 30 located adjacent the center sill, and a front wall 31 extending parallel to the side sill 11 and adjacent thereto, as shown in Figs. 2 and 3. The vertical front and 60 side walls of the chambers are provided with

laterally extending flanges 32, resting preferably directly against the under-face bottom wall 15 of the tank and secured thereto by rivets 33. The rear wall of each chamber is located adjacent the center sill and is 70 secured thereto by angle-brackets 34 and the rivets 7 and 35, the arrangement being such that the tank bottom 15 constitutes the upper wall of the heating chamber, so as to be directly subjected to the heat in said 75 chamber. Each chamber is individually heated, preferably by a liquid or gaseous fuel burner 36, preferably of the type provided for an admixture of the liquid or gaseous fuel with air supplied thereto under pressure, said burners being each connected by a fuel pipe connection 37 to a fuel-supply pipe 38, extending lengthwise of the car and connected to a suitable fuel-supply tank 39 carried by the understructure, each 80 of the connections 37 containing a manually-operable controlling valve 40, by means of which flow to each burner may be individually controlled. The burners are also connected, respectively, by air-supply pipes 85 41, each containing a hand-operable regulating valve 42, to a main supply pipe 43 leading from a tank 44 for containing compressed air, and mounted upon the understructure. The pipe 43 is connected by a 90 branch 43^a containing a hand-valve 43^b, said branch 43^a leading into the tank 39, whereby air under pressure may be admitted to said tank 39 to act on the fuel therein to force the same under pressure to the burners. 95 Each chamber is provided with a vertical, staggered baffles 45 extending from the bottom of the chamber to the tank bottom, and by means of which the flame from the burners is caused to take a circuitous path 100 through the furnace chamber, the latter being supplied with apertures 46 for admitting air thereto. At its rear portion, preferably, each chamber is provided with an outlet 47 through the bottom 15 of the tank; 105 the said outlets in the two innermost or adjacent chambers of each set to one side of the car understructure, and the corresponding set on the opposite side of the understructure, opening through the tank bottom 110 into a transverse collector chamber 48 within the tank body, and having a base flange 49 secured to the bottom wall 15 by rivets 50, and provided at its upper portion with an annular flange 51, to which is riveted, 115 as at 52, the lower end of a vertical flue or stack 53 extending upward from said collector through the body of the tank and secured to the upper wall of the latter by means of an annular angle-iron or pipe-flange 54, the vertical and horizontal flanges of which are riveted, respectively, as at 55 and 56, to the stack and to said top wall, 120 said flue or stack discharging through an opening in said top wall, as clearly shown in 125 130

Fig. 3. The said openings 47 in the end chambers on opposite sides of the center sill open into collectors 48^a, similar in construction to the collector 48, heretofore described, and connected by flues or ducts 53^a to the flue or stack 53, heretofore described. From the above description, taken in connection with the drawings, it will be seen that the flame, and heated air and gases in the furnace chambers, will come into direct contact with the bottom of the tank and hereby subject the same to the desired temperature, and flowing in a circuitous path through said chambers, will pass from the latter through the collectors 48, 48^a and stacks or flues 53, 53^a through the body of the material contained in the tank, so that not only is the material resting on the tank bottom subjected to the necessary temperature at that point, but said material is heated throughout its body by the heated products of combustion flowing through the flues or stacks 53, 53^a.

If desired, the stack 53 may be provided with a telescoping section 53^b normally nested within the said stack, but adapted to be projected therefrom vertically, and be held in extended position by holding-dowels 57 let through an annular angle piece or pipe-flange 58 surrounding the opening in the top of the tank and secured in place on the latter by the said rivets 56, said dowels serving to prevent the stack from being extended except when desired. The extensible portion 53^b may carry at its upper end an external collar or pipe-flange 59, in the form of an angle-iron, and riveted thereto, which not only serves to stiffen the same, but is adapted to cooperate with the angle-iron 58 and act as a stop thereagainst to limit inward movement of said extensible stack portion when lowered into the flue 53.

What I claim and desire to secure by Letters Patent of the United States is:

1. In a tank car, a tank body, a supporting underframe therefor comprising a center sill means for heating said body, comprising furnace chambers beneath said body and located on opposite sides of said center sill, and flues leading from said chambers and located in said tank body.

2. In a tank car, a tank body and means for heating the same, comprising furnace chambers beneath said body, a collector chamber in said body, openings through the wall of said body and leading from said furnace chambers into said collector chamber, and a discharge conduit communicating with said collector chamber and extending through the tank body.

3. In a tank car, a tank body, an understructure comprising sills supporting said tank body, means for heating said body comprising a plurality of chambers located beneath said body and riveted thereto, a gas-

eous fuel burner located in each of said chambers, and outlets from said chambers passing through said body, said chambers being located between the sills of said understructure.

70

4. In a tank car, a tank body and means for heating the same, comprising a plurality of chambers located beneath the same and riveted thereto, a gaseous fuel burner located in each of said chambers, outlets from said chambers, and a discharge stack extending through said tank body and having communication with said outlets from said chambers.

75

5. In a tank car, a tank body and means for heating the same, comprising a plurality of chambers located beneath the same and riveted thereto, a gaseous fuel burner located in each of said chambers, outlets from said chambers, and a vertical discharge stack in said tank body and opening through the upper portion thereof and having communication with said outlets from said chambers.

80

6. In a tank car, a tank body and means for heating the same, comprising a plurality of chambers located beneath the same and riveted thereto, a gaseous fuel burner located in each of said chambers, outlets from said chambers, a discharge stack extending through said tank body, and conduits in the tank body and connecting said outlets with said stack.

85

7. In a tank car, a tank body and means for heating the same, comprising a plurality of furnace chambers located beneath the tank body on opposite sides of the longitudinal axis of the latter, a gaseous fuel burner in each of said chambers and directed toward the center of the car, and supply pipes serving said burners and extending longitudinally of the car and beneath said tank body.

90

8. In a tank car, a tank body and means for heating the same, comprising a plurality of furnace chambers located beneath the tank body on opposite sides of the longitudinal axis of the latter, a gaseous fuel burner in each of said chambers and directed toward the center of the car, discharge flues for said chambers extending through the tank body, and supply pipes serving said burners extending longitudinally of the car and beneath said tank body.

95

9. In a tank car, a tank body, center sills supporting the tank body, a plurality of heating chambers arranged on opposite sides of the center sills and supported by the tank bottom and the center sills, fuel burners in said chambers, and flues communicating with said chambers through the tank bottom and extending through the tank body.

100

10. In a tank car, a tank body, center sills supporting the tank body, outwardly extending members connected to the center

105

110

115

120

125

130

sills, side sills supported by said members, a plurality of heating chambers for said tank body arranged on opposite sides of the center sills and supported by the tank bottom and center sills and enclosed in the space between the center sills, side sills and said outwardly extending members.

11. In a tank car, a tank body, furnace chambers located on opposite sides of the center line of the tank body, openings at the inner ends of said chambers through the tank bottom, a collector chamber in the

tank body and communicating through said openings with said furnaces, and a stack connected to said collector chamber and extending through the tank body.

In testimony whereof, I have hereunto signed my name, in the presence of two subscribing witnesses.

ABRAM E. SMITH.
